UNITED STATES PATENT OFFICE.

BURTON C. POSTON, OF CHILlicothe, OHIO.

COUCH BED.

Application filed January 26, 1921. Serial No. 439,947.

To all whom it may concern:

Be it known that I, BURTON C. POSTON, a citizen of the United States, residing at Chillicothe, in the county of Ross and State 5 of Ohio, have invented certain new and useful Improvements in Couch Beds, of which the following is a specification.

This invention relates broadly to improvements in household furniture, and has particular reference to an article of furniture which in the present instance is in the form of a convertible couch, and wherein features of construction are embodied for enabling the couch to be used for all ordinary purposes and yet to embody in the same an improved folding or collapsible bed structure, the latter being of such nature that when the couch is used for ordinary purposes, the bed structure formed therewith will be concealed from view, but by means of simple and efficient mechanism the said couch is capable of assuming an open position whereby the bed structure may be folded and properly presented for active use, the conversion of the couch into a bed being capable of being rapidly and conveniently accomplished and the several parts of the device maintained in their respectively adjusted positions.

The invention chiefly consists in the provision of an article of furniture of the aforesaid character wherein is included a couch or a sofa which is formed to provide a leg supported base structure having hingedly connected therewith a movable housing member, the latter having its upper surface suitably stuffed or padded and formed internally to provide a longitudinally extending chamber, and the said base structure being formed to include an improved collapsible and folding frame, which constitutes a part of the bed construction proper, the arrangement of the elements being such that when the couch is used for ordinary purposes, the said frame will be folded upon the upper part of the base structure and will lie within the chamber formed within the housing member and yet be capable, when the housing member is swung to assume a raised position, of being extended and suitably supported to produce a substantial, comfortable and accessible bed construction.

A further object of the invention resides in connecting the housing member and the base structure in such relationship that when the apparatus is opened to produce a bed

construction the housing member will be positioned to one side of the bed or base structure, and thereby assume a position which will not interfere with the occupants 60 of the bed structure so that the structure will be freely opened on all sides and unenclosed by the housing member.

A still further object of the invention resides in the provision of an automatic leg 65 structure for effecting the support of the housing member when the latter assumes an open vertical position.

With these and other objects in view, as will appear as the description proceeds, the 70 invention accordingly consists in the novel features of construction, combination of elements, and arrangement of parts, hereinafter to be fully described and pointed out in the appended claims.

In the accompanying drawings, in which similar characters of reference denote like and corresponding parts throughout the several views thereof:

Figure 1 is a side elevation disclosing my 80 improved couch-bed in its folded position adapted for imparting ordinary service.

Figure 2 is a vertical transverse sectional view taken along the plane disclosed by the line 2—2 of Figure 1, and illustrating more 85 particularly the internal construction of the housing member and the positions of the folded bed frames,

Figure 3 is an end elevation disclosing the 90 couch-bed in its open or extended position and adapted for service as a bed structure.

Figure 4 is a detail view in end elevation 95 disclosing the structure for effecting the vertical support of the housing member when the latter assumes its open position,

Figure 5 is a fragmentary top plan view.

Figure 6 is a detail front elevation disclosing the relationship between the bed frame and the intermediate pivotal support 100 therefor, and

Figure 7 is a detail view taken on the line 7—7 of Figure 6.

Referring more particularly to the details of the invention, the latter in the form disclosed in the accompanying drawings 105 consists essentially of a convertible couch-bed 1 which broadly includes a base 2 of rectangular form, a hingedly connected housing member 3 and a foldable bed frame 4. The base 2 in this instance includes vertical leg posts 5 which have their lower ends provided with rollers 6, and have their up-

per ends connected with transversely and longitudinally extending bars 7 and 8 respectively, the same being rigidly and securely united to produce a solid and substantial frame.

Suitably connected with the upper, longitudinally extending rear edge of the frame 4 is a plurality of hinges 9, which are also connected with adjacent longitudinal edge 10 portions of the housing member 3, the construction being such that the housing member may be pivotally swung to assume various positions with respect to the base construction. The said housing member in this 15 instance is formed to include a box like structure which consists of longitudinally extending spaced side rails 10, and end walls 11, which have their upper edges connected with a support 12, the latter acting to receive and retain suitable springs 13, which are utilized in conjunction with appropriate padding 14 to produce a stuffed and resilient seat structure 15 upon the upper portion of the said housing member, the latter being 20 of any suitable length and of appropriate design in order that the same may be adapted for the service to which couches are usually placed. It will also be noted that by this construction the interior of the housing member will be formed to comprise a 25 longitudinally extending chamber 16 of appreciable depth, the said chamber being defined between the base 2, the side and end walls of the housing member and the resilient seat structure 15 thereof.

Arranged to be normally positioned within the chamber 16 is a foldable bed frame 4, which when not in use is adapted to occupy the chamber 16 so as to be out of the way 40 and concealed from view. The said frame 4 in this particular embodiment includes a pair of rigid angularly extending brackets 17, which are carried upon the upper surfaces of the transverse bars 7 and are located within the chamber 16. These brackets are formed with elongated slots 18, which are adapted to receive pins or studs 19 which project rigidly from the U shaped frame 20 constituting one of the main parts of the 45 bed structure 4. The frame 20 in this instance is preferably formed from angle iron and includes a longitudinally extending rear portion 21 and forwardly projecting parallel sides 22 upon which the studs 19 are 50 formed, the said frame 20 being of such proportions as to be capable of normally lying within the chamber 16, and to be partially supported by the brackets 17. The forward ends of the sides 22 are pivotally connected 55 as at 23 with short intermediately disposed frame sections 24 which, when folded, assume substantially vertical positions.

The sections 24 are primarily utilized in effecting the support of the bed-frame structure 4 when the latter assumes an extended 60

position, and to this end the forward of the longitudinally extending bars 8 of the base 2 has its upper surface provided with a longitudinally extending metallic rod 25, the latter being intermediately bolted or otherwise secured as at 26 to the bar 8. The opposite ends of the rod 25 are upwardly bent as at 27 and are provided with rigid outwardly extending pintles 28, the latter being received within fixed metallic brackets 29 mounted upon the upper surfaces of the bars 7, the said pintles 28 being so situated as to pass intermediately through the sections 24 and to thereby pivotally support the frame structure 4 in its entirety.

The upper or outer ends of the sections 24 are pivotally connected as at 30 with angle iron rails 31 which form a part of the frame 4 proper, the said rails 31, when folded, being disposed to lie within the chamber 16 and to extend above and in parallel relation with the sides 22 of the frame 20, the outer ends of the rails 31 being in turn connected with a longitudinally extending rigidly connected rod 32, which is adapted to lie above and in parallel relation with the rear portion 21 of the frame 20. Also, as shown in Figure 5 particularly, the bed frame thus produced by the cooperative frame sections has the inside edges thereof connected with springs 33, which are utilized in conjunction with flexibly connected wires 34 to produce a resilient mattress support and yet to enable the frame 4 to be folded, as shown in Figure 2, without interference or obstruction.

In operation, the couch may be converted into a bed by swinging the housing member 3 bodily about its hinges 9 so that the said housing member will extend to one side of the base 2 and be capable of being supported in such a position by means of automatically operating legs 35. These legs, as shown in Figure 4, normally lie within the housing member and are slidably supported so as to be capable of projecting through openings 36 provided in one of the rails 10 thereof. The inner ends of the legs 35 are pivotally connected as at 37 with the outer ends of links 38, the latter having their inner ends pivotally connected as at 39 with the base 2. This arrangement is such that when the couch assumes the position disclosed in Figure 2, the legs 35 will be concealed within the walls of the housing member, but when the said member is swung to open the couch, the legs 35 will be automatically projected into engagement with the floor so as to support the housing in a substantially vertical position and to one side of the base 2. When the housing member is so raised the bed frame is conveniently accessible. Then, by grasping the rod 32 the rails 31 may be swung upwardly and outwardly until their horizontal flanges en-

- gage with the similar flanges provided upon the frame sections 24. When this engagement occurs the said sections 24 will be rocked about the pivots afforded by the 5 pintles 28, causing rearward movement to be imparted to the frame 20. Thus, when the rails 31 and their connected rod 32 approach an extended horizontal position, the frame 20 will be forced rearwardly and will 10 be raised vertically by the movement of the studs 19 within the slots 18 of the angularly extending brackets 17, and, as shown in Figure 3, when the sections have finally reached their extended and fully opened 15 positions the same will be located on the same horizontal plane, and at a desirable distance above the floor level.
- To limit the outward movement of the rails 31 and also to support the said rails 20 in their extended positions I employ pivoted leg pieces 40, which are pivotally mounted as at 41 upon the outer ends of the rails 31, the upper ends of the leg pieces 40 being pivotally connected with the outer ends of 25 links 42, the said links having their inner ends pivotally mounted about the pintles 28. This arrangement is such that when the rails 31 are fully extended, the leg pieces 40 will be swung automatically to a lowered 30 position and will serve to support the outer portion of the frame 4 and to relieve undue stress upon the main central support provided by the pintles 28. However, when the frame 4 is collapsed, the links 42 by 35 reason of their peculiar arrangement will serve to collapse the leg pieces and to retain the same substantially in parallel relation with the rails 31 within the chamber 16. It will be noted that by the provision 40 of the brackets 17, the frame 20 will be lowered when the structure 4 is collapsed so that the structure 4 may be compactly folded within the housing member and at the same time will enable the effective height of the 45 bed 1 to be maintained at conventional levels, and also, the said brackets 17 will serve to raise the frame 20 when the structure 4 is extended, so that the latter may be appropriately spaced from the floor level.
- If desired, the bars 31 may be equipped 50 with folding head and foot frames 43, which are suitably connected with coil springs 44, the latter serving to retain the frame 43 in an upright position when the structure 4
- is extended and also to retain the said frames 43 in a collapsed position upon the wires 34 when the structure 4 is folded. Mattress clamps 45 may be utilized for holding the rails 31 in their collapsed positions within the chamber 16, and to prevent the 55 resiliency exercised by a folded mattress from forcing the rails 31 upwardly into engagement with the support 12.
- From the foregoing description, taken in conjunction with the accompanying drawing, it will be apparent that the present invention provides an article of furniture which will possess a wide range of utility and yet will be capable of maintaining a 60 conventional appearance when adapted for ordinary use. The construction is such as to enable the apparatus to be easily and conveniently operated when the same is being converted from one use to another, and to permit this feature to be carried out with 65 but a minimum of labor and exertion. The parts of the bed structure 4 have been so formed as to be capable of being compactly folded and to be, therefore, easily inserted and retained within the chamber 16 provided within the housing member. In view of the above it is believed that the operation, construction and advantages of the invention will be readily understood by those 70 versed in the art, and therefore a more extended explanation has been accordingly omitted.
- What is claimed is:
- In a couch-bed, a base, a housing member 75 formed to include an internal chamber normally disposed above said base, a hinge connection between one of the lower edges of said housing member and said base and capable of permitting said member to be swung to assume a position substantially to one side of said base, and a foldable bed frame capable of occupying said chamber when said housing member assumes its normal position and to be extended to produce a bed structure when said member is elevated to occupy an open position, legs 80 mounted in the housing, and means for pivotally connecting the legs and base to cause said legs to slide when the housing member is swung in either direction.
- In testimony whereof I affix my signature.
- BURTON C. POSTON.
